UNITED STATES PATENT OFFICE.

EMIL POUYAT, OF LIMOGES, FRANCE.

DESIGN FOR A DISH.

SPECIFICATION forming part of Design No. 19,740, dated April 1, 1890.

Application filed December 23, 1889. Serial No. 334,793. Term of patent 14 years. Registered in France October 14, 1889, No. 278.

To all whom it may concern:

Be it known that I, EMIL POUYAT, a citizen of France, residing at Limoges, Department of Haute-Vienne, France, have invented and 5 produced a new and original Design for Dishes, of which the following is a specification, reference being had to the accompanying drawings, forming a part thereof.

Figure 1 is a profile view of a soup-tureen 10 or covered dish. Fig. 2 is a face view of a cover. Fig. 3 is the face view of a platter or deep dish. Fig. 4 is the face view of a plate, these four views being deemed necessary to fully illustrate my design.

15 The leading features of my design consist of a representation of flames shooting from the four corners of the dish or platter toward the center of the piece. The handles are plain scrolls turning upon themselves, at the extremities of which are leaves and sprays.

The soup-tureen or covered dish, Fig. 1, is 20 low and square, godrooned at the four corners, from which flames A A A A shoot out toward the center of the piece. The handles B B B are formed by a plain scroll turning 25 upon itself, the extremities of which bind

leaves and ornamental sprays. The base of the soup-tureen or covered dish is formed by eight scrolls C, holding leaves in one of the curved ends of each scroll.

30 The platter or deep dish, Fig. 3, is oblong, godrooned at the four corners, from which flames A A A A are represented as shooting out toward the basin of the dish. At each end the handles D D are in relief and have 35 the same shape of a scroll inclosing the leaves and sprays, as described above.

The outer circumference E of the plate, Fig. 4, is divided into four large and four small divisions. The inner circumference F 40 follows the form of the outer circumference E. Proceeding from the smaller divisions G, the flames shoot out toward the basin of the plate.

45 What I claim is—

The design for dishes herein shown and described.

EMIL POUYAT.
